US00D929690S

(12) **United States Design Patent** (10) Patent No.: **US D929,690 S**
(45) Date of Patent: **** Aug. 31, 2021**

(54) **SWEEPER**

(71) Applicant: **BEIJING XIAOMI MOBILE SOFTWARE CO., LTD.**, Beijing (CN)

(72) Inventors: **Zhaopeng Cheng**, Beijing (CN); **Lei Zhang**, Beijing (CN); **Yuan Gao**, Beijing (CN); **Ningning Li**, Beijing (CN)

(73) Assignee: **BEIJING XIAOMI MOBILE SOFTWARE CO., LTD.**, Beijing (CN)

(**) Term: **15 Years**

(21) Appl. No.: **35/508,833**

(22) Filed: **Sep. 18, 2019**

(80) **Hague Agreement Data**

Int. Filing Date: **Sep. 18, 2019**

Int. Reg. No.: **DM/205761**

Int. Reg. Date: **Sep. 18, 2019**

Int. Reg. Pub. Date: **Mar. 20, 2020**

(30) **Foreign Application Priority Data**

Mar. 18, 2019 (CN) 201930110366.8

(51) **LOC (13) Cl.** **15-05**

(52) **U.S. Cl.**

USPC **D32/21**; D15/199

CPC **A47L 9/009** (2013.01)

(58) **Field of Classification Search**

USPC D32/21, 23, 31; 15/319.353, 320, 339, 15/340.1, 383, 363, 340.4, 246.2, 384, 15/388, 392, 49.1; 180/6.2; 318/568.12; 901/1; D15/199

CPC A47L 9/009; A47L 2201/04

(57) **CLAIM**

The ornamental design for a sweeper, as shown and described.

DESCRIPTION

1. Sweeper

1.1 : Front

1.2 : Back

1.3 : Left

1.4 : Top

1.5 : Bottom

1.6 : Perspective

1.7 : Perspective

1.1 is a front elevation view of a sweeper of our new design; 1.2 is a back elevation view thereof; 1.3 is a left side elevation view thereof; 1.4 is a top plan view thereof; 1.5 is a bottom plan view thereof; 1.6 is a perspective view thereof; and 1.7 is another perspective view thereof.

1 Claim, 7 Drawing Sheets
